US00D793268S

(12) **United States Design Patent** (10) **Patent No.:** **US D793,268 S**
(45) **Date of Patent:** **** Aug. 1, 2017**

(54) **VIDEO DOORBELL**

(71) Applicant: **Shen Zhen Shi Fu Ying Xing Electronics Co., Ltd**, Shenzhen, Guangdong (CN)

(72) Inventor: **Binglei Ye**, Shenzhen (CN)

(73) Assignee: **Shen Zhen Shi Fu Ying Xing Electronics Co., Ltd**, Shenzhen (CN)

(**) Term: **15 Years**

(21) Appl. No.: **29/599,095**

(22) Filed: **Mar. 31, 2017**

(51) LOC (10) Cl. **10-05**

(52) U.S. Cl. .... **USPC D10/118.2**

(58) **Field of Classification Search**

USPC D10/104.1, 108, 116.1, 118, 118.2, 121, D10/122, 123, 124, 125, 126; D16/202, D16/203, 208, 209, 215; D13/171
CPC ... G08B 3/00; G08B 3/10; G08B 7/00; G08B 7/06
